UNITED STATES PATENT OFFICE

MICHAEL McCANN, OF ST. ALBANS, NEW YORK, ASSIGNOR TO FREDERICK OSANN COMPANY, OF NEW YORK, N. Y., A CORPORATION OF NEW YORK

MEANS FOR SHANKING BUTTONS

Original application filed February 12, 1930, Serial No. 427,785. Divided and this application filed January 17, 1931. Serial No. 509,390.

When buttons are sewed to the heavier types of garments such as overcoats, it is desirable that the back faces of the buttons be spaced from the forward face of the cloth so that the relatively thick material adjacent to the buttonholes may pass in between sufficiently readily when the garment is buttoned. It has been customary, therefore to sew the button on loosely and then to wind thread about the group of stitches between the button and the work to form a "shank" to space the button from the work. Attempts have been heretofore made to sew and "shank" buttons by machine, the same machine performing both operations. Such machines, however, have been highly complicated and to the best of my knowledge have never been commercially successful.

In accordance with the present invention shanking is done as an operation separate and distinct from the sewing and may be done by a machine of the button sewing type, differing therefrom only in the device for holding the work and in the mechanism for controlling the movement of the work relative to the sewing needle. The button is first sewed to the work sufficiently loosely to form a "neck" of threads between the rear face of the button and the front face of work as by holding the button spaced from the work the desired distance during the sewing operation. The button and the work are then so supported and manipulated relative to a sewing needle as to wrap the neck of threads substantially from end to end, the stitches being passed alternately about opposite sides of the neck of threads and preferably distributed lengthwise of this neck. Either a chain or a lock stitch machine may be used for this operation, successively placed loops of shanking thread passed about the neck of sewing threads being locked together either in chain stitch formation when a chain stitch machine is used, or through a second or shuttle thread when a lock stitch machine is used. In either case the stitching action tightens the loops of thread about the neck strands so that a very satisfactory shanking action results which is more secure and more uni-

formly distributed than that produced by the usual hand winding.

The present application relates only to the sewing machine for effecting the shanking operation, being a division of application Serial No. 427,785 filed February 12, 1930 for shanking buttons.

For a more complete understanding of this invention, reference may be had to the accompanying drawing in which

Figure 1 is a side elevation partly broken away of a button sewing machine equipped to perform the shanking operation and showing the button and work in position therefor.

Figure 2 is a horizontal section on line 2-2 of Figure 1, the button and work being omitted.

Figure 3 is a fragmentary perspective of the holder for the button and work.

Figure 4 is a front elevation of a button clamp and button held in proper relation to work in a button sewing machine for the sewing operation preparatory to shanking.

Figure 5 is a somewhat diagrammatic view to a large scale and with parts distorted for the sake of clarity and illustrating the shanking operation.

Referring to the drawing, Figures 1 and 2 illustrate a well known button sewing machine of the chain stitch type such as is shown more in detail in the Lyons Patent No. 1,671,197, granted May 29, 1928. This machine has a base 1 from which extends upwardly and forwardly a sewing arm 2 having a head 3 at its free end in which is mounted for reciprocation and pivotal movement about an axis 4, a needle bar 5. This needle bar is given its reciprocating motions by a rock shaft 6 connected to the needle bar by the pivoted arms 7 and 8. The lateral motion of the needle bar about the pivot 4 is produced by rocking of an arm 9, adjustably pivoted at 10 to determine the amplitude of lateral motion, as is more fully disclosed in the Lyons patent. In the base 1 is a suitable looper mechanism 11 which cooperates with the needle 15 carried by the needle bar 5 to form chain stitches.

In place of the usual button clamp employed with button sewing machines of this

type, a special form of work holder indicated as a whole at 20 is employed. This holder, as shown, comprises a base 21 which is pivotally connected as at 22 through a bracket 5 arm 24 to a slide 220, this pivot being horizontally disposed so that the base 21 may be raised when desired as by pulling on a chain 25 secured at its lower end to a block 26 bolted to the base 21. This chain may be 10 pulled upwardly by any suitable means, but as herein shown its upper end is pivoted to an arm 27 carried by a rock shaft 28. This rock shaft is normally held in such an angular position as to permit the base 21 to rest 15 in contact with the usual throat plate 90 of the machine, as by means of a coil spring 29. This rock shaft 28 may be turned so as to raise the work holder by any suitable means for example, as disclosed in the Lyons patent 20 by means of a pull chain extending to a suitable treadle mechanism.

At the forward end of the base 21 are positioned a pair of upstanding wall members 30 and 31 which are arranged laterally to the 25 length of the base 21. The wall member 31, as shown, is provided with a rearwardly directed integral foot plate 32 which may be adjustably fixed to the base 21 as by means of a screw 33 passing through a slot 34 there- 30 in and threaded into the base 21. The wall member 30 is provided with a similar foot portion 36 through which is a slot 37 for the reception of a securing screw 38 which is also threaded into the base 21. The plate 35 members 30 and 31 are provided with opposed slots 40 and 41, respectively, preferably having rounded flaring upper ends to facilitate inserting the work. The slot 41 is somewhat wider than the slot 40 for a pur- 40 pose which will later appear. These plate members form a support for a button and the work which have previously been loosely stitched together in such a manner as to leave a neck of stitching threads 45 therebe- 45 tween, the back face of the button 46 being positioned against the back face of the wall member 31 and the work 47 to which it is attached being positioned forwardly of the wall member 30, the stitching threads ex- 50 tending through the notches 40 and 41. In order to better retain the work and button in position the members 30 and 31 may be spaced apart at their upper portions slightly fur- 55 ther than at their foot portions, as shown. 55 This preliminary securing of the button to the work in this loose manner may be effected by any suitable mechanism. In Figure 4 is shown, for example, a button clamp indicated generally at 50 provided with side 60 button clamping jaws 51 and 52 which are shown as provided with downwardly extending feet 53 and 54 which rest upon the upper face of the work 47 so as to support the button 46 spaced thereabove so that when the 65 stitches are passed through the sewing holes

of the button and the work, the button is loosely secured by the stitching threads as heretofore described. Commonly where the work to which the buttons are secured is heavy, such as overcoating fabric, a reinforcing button is applied to the back face of the work and where this is desired the cloth plate 56 of the button sewing machine may be provided with a depression to receive the reinforcing button as at 57 and hold it in proper relation to the button clamp so that the stitching threads are passed through sewing holes in this reinforcing button as well as through the work and the button being secured. This reinforcing button may be 70 omitted, if desired. The plates 30 and 31 are so positioned relative to the needle that the needle strokes are caused to pass alternately on opposite sides of the neck of threads, thus to cause successive loops of stitching thread 75 to be passed about this neck of threads alter- 80 nately in opposite directions. Thus when these loops of thread are taken from the needle, as by the usual looper mechanism, and the stitch is completed, these loops are drawn 85 up tightly about the neck of threads, bind- 90 ing them together by the interengagement of these loops. Where, as in the machine illustrated, a chain stitch machine is used, these loops will be interengaged with each 95 other in chain stitch formation, as shown somewhat diagrammatically at 60 in Figure 5, though it will be understood that these loops will be drawn tightly together as in 100 the usual chain stitch sewing operation and not loosely as they are shown for the sake of clarity. The slot 40 on the plate 30 is prefer- 105 ably sufficiently narrow to bring the sewing threads of the neck so close together that the lateral vibratory motion of the needle be- 110 tween successive stitching operations is suf- 115 ficient to clear the neck of threads when given an amplitude of motion which may, if de- 120 sired, be identical with that employed in the placing of the securing stitches through the 125 sewing holes in the button. The button being of relatively unyielding material holds the groups of stitching threads apart adjacent thereto so that the slot 41 is made relatively 130 wide to receive them.

Between successive stitching operations, it is preferable to move the work and button holder lengthwise of the neck of threads in order to distribute the binding threads there- 135 along throughout a definite length. Button sewing machines of the character shown are commonly provided with means for producing such motion of the button clamp and it is only necessary therefore to apply to such machines cam or other controlling mechanism designed to impart the desired motion to the button and work holder 20 for the purposes of the present invention. To this end the machine shown is provided with a cam 70 having a cam path 71 therein within which

rides a follower 72 on an arm 73 fixed to a rock shaft 74. This rock shaft imparts motion to a slotted link 75 in a manner clearly disclosed in the Lyons patent hereinbefore referred to and which is adjustably connected to move the slide 220. The cam path 71 as shown is formed to impart motion by small increments to the slide 220 between successive passes of the needle 15. It is shown as 10 designed to start the shanking operation adjacent to the plate 30 where the sewing threads have been brought together by the relatively narrow slot 40. As the operation of the machine progresses, the button and 15 work are moved forwardly so as to cause the shanking to be effected progressively toward the rear face of the button until the space between the plates 30 and 31 have been substantially filled by binding stitches. The 20 work and button are then given a step by step rearward movement until they are brought back to their initial position where the machine stops. Two superposed layers of wrapping stitches are thus passed about 25 the neck of threads in each machine cycle. As usual with machines of this type the two final needle strokes may be caused to pass on the same side of the neck of sewing threads to knot the thread in the usual manner.

30 For ease in adjusting it is preferable that the forward position of the work and button holder be the same for all adjustments of the throw of the work and button. Thus after the rear plate 31 has been fixed in the 35 proper position for one length of shank, it is then necessary only to adjust the position of the forward plate 30, which is readily accessible, when the length of shank is to be modified. In order that buttons of relatively large size may be taken by the holding means, the base 32 of the plate 31 may be slotted out as at 80 and this slot may be extended through the base plate 21 and into the throat plate 90 as shown in Figure 1.

45 From the foregoing description of the method of shanking, a machine for performing the operation and the resultant product, it should be evident to those skilled in the art that various changes and modifications 50 might be made without departing from the spirit or scope of this invention. I do not claim herein broadly the wrapping of strand or other material gathered together in bundle formation by loops of thread passed alternately thereabout in opposite directions and secured together, but what I do claim is:

1. In combination, means for holding in spaced relation a button and work to which said button is loosely secured by stitches to 55 form a neck of stitching threads extending therebetween, and means for wrapping a definite length of said neck with loops of thread passed thereabout in opposite directions and secured together.
- 60 2. In combination, means for holding in

spaced relation a button and work to which said button is loosely secured by stitches to 70 form a neck of stitching threads extending therebetween, and means for wrapping a definite length of said neck with loops of thread passed thereabout in opposite directions and secured together in chain stitch formation.

3. In combination, sewing means, means for holding a button and work to which it is 75 loosely secured by stitches in spaced relation to form a neck of stitching threads therebetween, and means for relatively moving said holding and sewing means a predetermined amount during a sewing operation to cause stitches made by said sewing means to be passed about and be distributed along a definite length of said neck and to be secured together.

4. In combination, sewing means, means for holding a button and work to which it is 80 loosely secured by stitches in spaced relation to form a neck of stitching threads therebetween, and means for relatively moving said holding and sewing means lengthwise of said neck a plurality of times during the sewing operation to cause stitches made by said sewing means to be passed about said neck and to be secured together and distributed in superposed layers throughout substantially the full length of said neck.

5. In combination, means for holding in spaced relation a button and work to which said button is loosely secured by stitches to 90 form a neck of stitching threads extending therebetween, sewing mechanism for passing stitches alternately in opposite directions about said neck and securing them together in neck wrapping relation, and means for moving said holding means axially of said neck as the sewing mechanism operates to distribute the wrapping stitches along said neck between the button and the work.

6. In combination, means for holding in spaced relation a button and work to which said button is loosely secured by stitches to 100 form a neck of stitching threads extending therebetween, sewing mechanism for passing stitches alternately in opposite directions about said neck and securing them together in neck wrapping relation, and means for moving said holding means axially of said neck in one and then in the opposite direction as the sewing mechanism operates to distribute the wrapping stitches along said neck between the button and the work in superposed layers.

7. In a sewing machine, a work holder 110 comprising a base, a pair of plates extending from said base in spaced substantially parallel relation and having opposed slots extending toward said base to receive the stitches loosely connecting a button positioned outwardly of one of said plates with work positioned outwardly of the other of 120

said plates and to hold said stitches in taut condition in neck formation, sewing instrumentalities including a needle movable laterally of and past said sewing 5 stitches, and means for taking loops of thread from said needle and completing stitch formation therewith, means for moving said work holder and needle relatively between successive needle strokes to cause said strokes 10 to pass alternately on opposite sides of said neck of stitches and means for relatively moving said holder and sewing means axially of said neck to cause stitches formed by said securing means to be distributed lengthwise 15 of said neck.

8. A work holder comprising a base member, and a pair of plate members supported by said base member in substantially paral-

lel relation, said plate members having opposed slots extending toward said base for receiving the stitches extending between a button engaging the outer face of one of said plates and work engaging the outer face of 70 the other of said plates.

9. A work holder comprising a base member, and a pair of plate members supported by said base member in substantially parallel relation and adjustable toward and from 75 each other, said plate members having opposed slots extending toward said base for receiving the stitches extending between a button engaging the outer face of one of said plates and work engaging the outer face of 80 the other of said plates.
